(57) **CLAIM**

The ornamental design for a vehicle door trim set, as shown and described.

DESCRIPTION

FIG. 1 is a front perspective view of the front left-side component for the vehicle door trim set;
FIG. 2 is a rear perspective view thereof;
FIG. 3 is an exterior side elevation view thereof;
FIG. 4 is an enlarged front view thereof;
FIG. 5 is an enlarged rear view thereof; and
FIG. 6 is a top plan view thereof.
FIG. 7 is a rear elevation view of the front left-side component for the vehicle door trim set installed into an environmental front door panel;
FIG. 8 is a front elevation view thereof;
FIG. 9 is a front perspective view thereof;
FIG. 10 is a rear perspective view thereof; and
FIG. 11 is an exterior side view thereof.
FIG. 12 is a front perspective view of the front right-side component for the vehicle door trim set;
FIG. 13 is a rear perspective view thereof;
FIG. 14 is an exterior side elevation view thereof;
FIG. 15 is an enlarged front elevation view thereof; and
FIG. 16 is an enlarged rear view thereof.
FIG. 17 is a front perspective view of the rear left-side component for the vehicle door trim set;
FIG. 18 is a rear perspective view thereof;
FIG. 19 is an exterior side elevation view thereof;
FIG. 20 is an enlarged rear elevation view thereof;
FIG. 21 is an enlarged front elevation view thereof; and
FIG. 22 is a top plan view thereof.
FIG. 23 is a front perspective view of the rear right-side component for the vehicle door trim set;
FIG. 24 is a rear perspective view thereof;
FIG. 25 is an exterior side elevation view thereof;
FIG. 26 is an enlarged rear elevation view thereof;
FIG. 27 is an enlarged front elevation view thereof; and
FIG. 28 is a top plan view thereof; and,
FIG. 29 is an exterior side view of the vehicle door trim set incorporated into the doors of a motor vehicle.
The de-emphasized and halftone portions shown in the drawings illustrate environmental structure for the vehicle door trim set that forms no part of the claimed design.
